UNITED STATES PATENT OFFICE.

MILTON S. LYSINGER, OF NORRISTOWN, PENNSYLVANIA.

DYNAMO.

1,129,700.

Specification of Letters Patent. Patented Feb. 23, 1915.

Application filed June 19, 1912. Serial No. 704,611.

To all whom it may concern:

Be it known that I, MILTON S. LYSINGER, a citizen of the United States, residing at Norristown, in the county of Montgomery 5 and State of Pennsylvania, have invented new and useful Improvements in Dynamos, of which the following is a specification.

This invention relates to dynamos, the object in view being to provide a light construction of revolving armature which embraces and rotates around a stationary core mounted on a fixed shaft, the armature being provided with a hollow shaft carrying a commutator, to which the windings of the 15 armature are connected. On account of the light weight of the revolving armature, the same may be driven at a very high speed with great economy of power.

With the above and other objects in view, 20 the invention consists in the construction, combination and arrangement of parts, as will be hereinafter more fully described, illustrated in the accompanying drawings, and pointed out in the claim hereunto appended.

In the drawings: Figure 1 is a central longitudinal section through a dynamo, embodying the present invention. Fig. 2 is a cross section through the core and field.

Referring to the drawings, 1 designates the outer casing or housing of the dynamo, in which is arranged a central iron core 2 mounted fast upon a stationary shaft 3 mounted at its ends in suitable fixed bearings 35 forming extensions of the opposite ends of

the casing or housing arranged concentrically around the stationary shaft 3 and attached to the inner surface of the casing 1 is a series of field magnets 10. Extending around the core 2 is a revolving cylindrical armature, embodying a brass body having suitable windings thereon. This cylinder 4 is attached, at its opposite ends, to heads 5 and 6, and these heads are provided with outwardly extending hollow shaft sections 45 7 and 8, which are journaled upon the stationary shaft 3. To the hollow shaft section 7 there is connected a commutator 9, in connection with which suitable brushes may be used for carrying off the current generated by the dynamo.

What is claimed is:

A dynamo comprising a casing, a shaft fixed in said casing, electro field magnets arranged in the casing, a central core fixed with relation to the magnets, an outer cylindrical armature adapted to revolve around the core and within the field generated by said magnets, collar shaft extensions supporting said armature and mounted upon 55 said fixed shaft, a commutator mounted upon one of the shaft extensions within the casing, and a driving element mounted upon the other shaft extension beyond the casing.

In testimony whereof I affix my signature 60 in presence of two witnesses.

MILTON S. LYSINGER.
